PRINTING MACHINE

William F. Huck, Richmond Hill, N. Y., assignor
to R. Hoe & Co., Inc., New York, N. Y., a corporation of New York

Application March 13, 1939, Serial No. 261,480

16 Claims. (CL 101—348)

This invention relates to rotary printing machines and more particularly to improvements in printing mechanism therefor.

The new and useful features and principles of this invention are especially applicable to multi-color offset lithographic printing machines, wherein fixed oil-tight bearings are provided for the ink distributing cylinders, and wherein certain of the inking rollers rotate about fixed centers. As it is necessary, in such types of rotary printing machines, to occasionally separate, or trip the various cylinders and inking rollers, this invention contemplates as one of its principal objects, the provision of an improved combined and selectively operable cylinder and ink roller tripping mechanism.

Another object of the invention is to provide in a printing machine an improved roller reciprocating mechanism.

Still another object is to provide an improved ductor roller mounting and an improved adjustable actuating mechanism therefor.

Further objects include the provision of improved locking devices for roller socket screws and the provision of improved bearing mountings and supports for ink rollers.

It is also an object of this invention to provide a rotary printing mechanism of generally improved construction, whereby the mechanism will be simple, durable, and inexpensive in construction, as well as convenient, practical, serviceable, and efficient in its use.

With the foregoing and other objects in view, which will appear as the description proceeds, the invention resides in the combination and arrangement of parts, and in the details of construction hereinafter described and claimed.

A preferred embodiment of the invention is illustrated in the accompanying drawings, wherein:

Figure 1 is a diagrammatic illustration of a multi-color lithographic printing machine embodying the features and principles of this invention;

Figure 2 is a perspective view of several of the cooperating cylinders and inking rollers of one of the units of the machine shown in Figure 1, certain parts being broken away and others omitted for the sake of clearness;

Figure 3 is an elevation partly in section of an inking roller showing the reciprocating mechanism therefor, the view being taken on line 3 of Figures 1 and 4 looking in the direction of the arrows;

Figure 4 is a view of the reciprocating mecha-

nism shown in Figure 3 and taken on line 4 of that figure and looking in the direction of the arrow;

Figure 5 is a broken sectional view taken on line 5—5 of Figure 3;

Figure 6 is an end view of certain parts shown in Figure 5;

Figure 7 shows a form cylinder and certain ink rollers with their bearings and cooperating mechanism in the relation indicated by the zig-zag line 7—7 of Figure 8;

Figure 8 is a sectional view taken on line 8—8 of Figure 7;

Figure 9 is a view similar to Figure 8 but showing the parts in another position with the inking rollers in tripped position;

Figure 10 is an enlarged view partly in section taken on line 10—10 of Figure 8;

Figure 11 is an enlarged sectional view taken on line 11 of Figure 8;

Figure 12 is an enlarged face view of a portion of the tripping mechanism;

Figure 13 is a side view of the parts shown in Figure 12;

Figure 14 is a sectional view taken on line 14—14 of Figure 13;

Figure 15 is a top plan view of another portion of the tripping mechanism and looking in the direction of arrow 15 in Figure 16; and

Figure 16 is a sectional view taken on line 16—16 of Figure 15.

The printing machine diagrammatically shown in Figure 1 comprises a plurality of perfecting printing units 21, arranged to print simultaneously on both sides of the web 22 as it passes between the cylinders 23 and 24 of each unit. The printing machine shown is of the type known as an offset perfecting press, but it is to be understood that the features and principles of this invention are not to be limited to the particular type of printing machine herein shown. The cylinders 23 and 24 in this instance are the printing or blanket cylinders and receive the impression to be printed upon the web 22 from form or plate cylinders 25 and 26 respectively.

The respective cylinders 23, 24, 25 and 26 are arranged to be driven from a shaft 27, which in turn is preferably driven by a motor 28 geared to the shaft 27 by bevel gears 29 and 31. The cylinder 23 is drivingly connected to the shaft 27 by means of a worm 32 and a worm-wheel 33 indicated diagrammatically in Figure 1. The cylinder 24 is driven from the cylinder 23 through gears 34 and 35, the outer peripheries of these gears rather than their pitch lines being shown

55

in dotted lines in Figure 1. The cylinder 25 is driven from the cylinder 23 by a gear 36 in mesh with the gear 34, and the cylinder 26 is driven from the cylinder 24 by a gear 37 in mesh with the gear 35.

Ink fountains 38 and 39 are provided and contain ink for the forms or plates on the cylinders 25 and 26 respectively, each fountain 38 and 39 having the usual rotating fountain roller 41 therein. A swingably mounted ductor roller 42 is provided to take ink from each of the fountain rollers 41 and transfer it to a reciprocating ink roller 43, wherever the ink is spread by a pair of rollers 44. The ink is then transferred from the roller 43, through rollers 45 and 46, to a pair of reciprocating ink rollers 47 and 48, spaced apart about the cylinders 25 and 26. From each of the rollers 47 and 48, the ink is carried to the plates on the cylinders 25 and 26 by ink form rollers 49 and 50.

Water fountains 51 and 52 are provided to supply moisture for the printing plates or forms, each fountain having the usual rotatable fountain roller 53 therein. A swingable ductor roller 54 carries water from the fountain roller 53 to reciprocating moisture rollers 55, wherefrom moisture is carried to and distributed on the plates on the cylinders 25 or 26 by form moistening rollers 56.

As shown in Figure 7, the reciprocating ink rollers and moisture or water rollers 47, 48 and 55 are arranged to be driven by means of suitable gearing from their associated cylinders 25 or 26, through an idler gear 57 in mesh with the respective gears 36 and 37, and an idler gear pinion 58 rotatable with the gear 57 and in mesh with a gear 59 on one end of a shaft 60 of the respective reciprocating ink or water roller. Each of the swingable ductor rollers 42 and 54 are arranged to be swung in the same manner from the respective fountain rollers 41 and 53 to the respective reciprocating ink and water rollers 43 and 55, by means of a rotatable cam 61, one of which cams is shown in Figures 1 and 2, and it will be understood that similar operating mechanism is provided for the ductor rollers in the lower portion of each printing unit. The cam 61 is arranged to be rotated from the shaft of the reciprocating ink roller 47, through an idler gear 62 which is in mesh with the gear 59 on the shaft of the roller 47, and a gear 63 on the shaft of the cam 61, also in mesh with the gear 62.

The connection between the cam 61 and the ductor roller 42 (see Figures 1 and 2), includes a lever 64 secured on a shaft 65 extending between and journaled in machine frame members 66 and 67. One of the shaft ends 68 and 69 of the ductor rollers, for instance the shaft end 68 of the roller 42, is journaled in one arm 71 of the lever 64, and the other shaft end 69 is journaled in one arm 72 of a lever 73, which is secured near the other end of the shaft 65. The other arm 74 of the lever 64 is connected by a link 75 to an arm 76 which has an arcuate slot 77 formed therein, the arc of the slot 77 being concentric to the pivotal point of the link 75 on the arm 74 when the ductor roller 42 is in engagement with the fountain roller 41. The link 75 is adjustably connected to the arm 76 by means of a clamp screw 78 slideable in the slot 77. The arm 76 is secured on one end of a short rocker shaft 79 which is journaled in the frame member 66. An arm 81 secured on the shaft 79 has a roller 82 on its free end which is adapted to ride on the periphery of the cam 61. By means of the link 75

75 and its adjustable connection with the arm 76 in the arcuate slot 77, the throw of the ductor roller 42 toward the ink roller 43 may be adjusted to vary the pressure of its engagement therewith without changing the pressure of the engagement of the roller 42 with the fountain roller 41.

Coiled springs 83 are provided to react between studs 84 secured to the frame members 66 and 67 and the arm 74 of the lever 64, and another arm 85 of the lever 73 to maintain the roller 82 against the cam 61, and press the ductor roller 42 toward the fountain roller 41. A swingable catch member 86 is pivoted to the frame member 67 and is adapted to be swung into the path of a lip 87 formed on the end of the arm 85 of the lever 73, to hold the ductor roller 42 out of contact with the fountain roller 41. The ductor roller 42 is rotatably supported in the arms 71 and 72 in a manner identical with the arrangement for supporting the form rollers 49 and 50 and hereinafter described.

The mechanisms (see Figures 1-7 inclusive), for reciprocating the ink and water rollers 43, 47, 48 and 55 are substantially identical and include the gear 59 on one end of the shaft 60 of the respective roller, and the other end 88 of this shaft 60. The shaft end 88, as best shown in Figure 3, extends through the frame member 66, in which it is journaled to rotate on a fixed axis, and into an oil-tight casing 89. A worm gear 91 is secured to the shaft end 88 within the casing 89 and meshes with a worm gear wheel 92 having hubs 93 and 94 journaled in the sides of the casing 89. The casing 89 is supported upon a reduced portion 95 of the end 88 of the roller shaft 60 and is reciprocated with the respective ink roller, being guided and prevented from rotating with the shaft by rollers 96 and 97 pivotally supported on the casing and disposed to engage and ride one on either side of a bar 98, secured to and extending from the frame member 66. Both ends of the ink roller shaft 60 are journaled in roller bearings 99 secured in the frame members 66 and 67 and are adapted to rotate as well as to slide axially therein. The worm-wheel 92 is provided with an eccentric bore adapted to receive a shaft 101 which is held against axial movement therein by means of a pin 102 passing through the hub 94 and engaging a groove 103 in the shaft 101 to permit relative rotation between the shaft 101 and the worm-wheel 92. The shaft 101 is thus eccentric to the worm-wheel 92 and has gudgeons 104 and 105 extending from its ends, the gudgeon 104 being hollow. The gudgeons 104 and 105 are formed eccentric to the shaft 101. A clamp bolt 106 passes axially through the gudgeon 104 and one end of the shaft 101 and is screw-threaded into a block 107 disposed in a recess 108 provided in the shaft 101. The block 107 is adapted to lock the shaft 101 to the worm-wheel 92 when the bolt 106 is tightened, by being wedged between an inclined bottom surface 109 of the recess 108 and the surface 111 of the bore in the worm-wheel 92.

A screw 112 is screw-threaded into a gudgeon 105 and secures a disc 113 in position as shown in Figure 5. The disc 113 is provided with a lug 113a on its inner side which fits into a cross-groove 114 formed on the end of the gudgeon 105. The disc 113 has a hexagon-shaped boss 113b on its outer side and it will be understood that by applying a suitable wrench to the hexagon boss, the shaft 101 may be rotated when the block 107

is loosened, to adjust the eccentricity of the gudgeons 104 and 105 relatively to the worm-wheel 92. A lever 115 is pivoted upon each gudgeon 104 and 105 and has one of its ends pivotally connected to one end of a link 116, the other end of which is pivotally connected to the casing 89. The other end of each lever 115 is pivotally connected to one end of a link 117, the other end of which is pivotally connected to 117a to a member 117b secured to the frame member 66. The pivots 117a are in alignment and they are preferably so positioned that their axis intersects the axis of the shaft end 88.

By means of the above-described roller reciprocating mechanism, the reciprocating ink and water rollers are given an axial reciprocating movement whenever they are rotated through the gear 89. This movement is due to the rotation of the gudgeons 104 and 105 about the axis of the worm-wheel 92, whereby the lever 115 is rocked upon its pivotal connection with the link 117 and slides the casing 89 along the bar 98 and the shaft 60 of the reciprocating ink and water rollers axially in its bearings in the frame members 66 and 67. By adjusting the eccentricity of the gudgeons 104 and 105 relatively to the worm-wheel 92, the length of the stroke of the respective roller may be varied. Due to the novel arrangement of cranks and levers, the pivotal connection at which the thrust of the lever 115 is applied to the link 117, moves in an elliptical path and the force is exerted with much less side pressure than is present where a simple crank action is used. Hence, there is practically no tendency to bend or bind the shaft 60 in its bearings.

As shown in Figures 1 and 2, the improved mechanism for tripping the form inking rollers 49 and 50, the form moistening rollers 56, the form cylinders 25 and 26 and the upper blanket cylinder 23 includes a crank arm 118, one end of which is pivotally mounted on a crank pin 119 extending from and eccentric to a shaft end 121 of the lower printing or blanket cylinder 24. The other end 122 of the arm 118 is provided with catch shoulders 123 and 124, one on each side edge thereof. The catch shoulders 123 and 124 are adapted to engage pins 125 and 126 respectively between which the arm 118 can be swung. The pins 125 and 126 extend between spaced apart bars 127 and 128, the bar 127 having a squared end 129 adapted to receive a wrench, and the bar 128 being secured on the end of a shaft 131 which extends between and is journaled in the frame members 66 and 67. Engagement of the catch shoulder 123 on the reciprocating arm 118, with the pin 125 will rock the shaft 131 in one direction, and engagement of the catch shoulder 124 with the pin 126 will rock the shaft 131 in the other direction.

Means whereby the engagement of the pins 125 and 126 by the catch shoulders 123 and 124 is controlled includes links 132 connected to the end 122 of the arm 118 and to the free end of an arm 133 pivotally supported on the frame member 66. The arm 133 is connected to a lever 134 by a rod 135 which is pivotally connected to a short arm 136 of the lever 134 and extends to end through a lug 137 on the arm 133. A spring 138 is coiled about the rod 135 and reacts between it and the lug 137 to constantly urge the arm 133 in a direction to maintain the arm 118 in position for the shoulder 123 to engage the pin 125. The long arm 139 of the lever 134 has a sleeve 141 (best shown in Figures 12 and 14) secured

thereto by a nut 142 and has a handle 143 upon its free end. The sleeve 141 is slidably mounted on a rod 144 and disposed in an elongated opening 146 formed in a frame 145. The rod 144 passes lengthwise through and is secured to the frame 145 by nuts 147 and 148. The sleeve 141 is disposed between collars 149 and 151 which normally abut against shoulders 152 and 153 respectively provided on the frame 145 and which extend inwardly from the sides of the opening 146. Springs 154 and 155 coiled about the rod 144 react between the collars 149 and 151 and the respectively adjacent ends of the opening 146.

Movement of the rod 144 to the left will swing 15 the lever 134 and relieve the pressure of the spring 138 against the lug of the arm 133. The arm 133 will then be swung downward by gravity and the catch shoulder 124 will engage the pin 126 and trip the cylinders "off impression" as hereinafter described.

As shown in Figure 1, the rod 144 extends along the side of all of the units 21. On one of the units the rod 144 passes through a guide 144a and collars 144b and 144c are secured to the rod on either side of the guide. A spring 144d is placed upon the rod 144 between the guide 144a and the collar 144c and acts to force the rod 144 to the right as shown in the drawings, to the extent permitted by the collar 144b.

30 A switch 156 and conductors 157 provide means to energize a solenoid 158 or like device, to actuate a bell crank 159 and thereby move the rod 144 towards the left as shown in the drawings, and simultaneously rock the shafts 131 of all of 35 the units 21 in the proper direction to trip the cylinders and form rollers "off impression." If, however, any of the levers 139 are locked in either the "impression on" or "impression off" position, they obviously will not be affected by the movement of the rod 144 by the solenoid.

40 The means whereby the various rollers and cylinders are simultaneously tripped in the directions indicated by the arrows 160 in Figure 1, when the shaft 131 is rocked in a counter-clockwise direction includes arms 161, (Figure 1) secured on the shaft 131, (Figure 2) and links 162 (Figure 1), pivotally connected to the arms 161 and being secured to and extending to lugs 163 provided on rings 164 which are secured to the 45 hubs 165 of bushings 166.

45 The bushings 166 are mounted in the frame members 66 and 67 and support the bearings 167 of the upper blanket cylinder 23. The bushings 166 are arranged eccentric to the bearings 167 so that rotation of the bushings 166 will raise the axis of the cylinder 23 and separate its peripheral surface from the cooperating peripheral surface of the lower blanket cylinder 24. The form and 50 operation of the rings 164 and the eccentric bearing supporting bushings 166 shown in operative position in respect to the cylinder 23, is similar to that of rings 168 (see Figure 7), which are secured to the hubs 169 of eccentric bearing supporting bushings 171 and support the bearings 173 55 of the form or plate cylinders 25 and 26. The rings 168 are connected by horizontal links 174 (see Figures 2 and 7), to vertical links 175 at a point 176 spaced from the upper end of the links 175.

60 70 The lower ends of the links 175 are connected by bars 177 to arms 178 secured on a shaft 179 which extends between and is journaled in the frame members 66 and 67. The shaft 179 has a handle 181 secured thereto adjacent the frame member 66 by which it may be manually rocked.

The upper ends of the links 175 are connected to arms 182 and 183 (see Figures 2, 15 and 16), which are secured one on each end of a tubular shaft 184 by screws 185. The tubular shaft 184 is rotatably mounted on and supported by a shaft 186 extending between and journaled in the frame member 66 and 67. A coiled spring 187 is provided to react between the arm 182 and a stationary stud 188 extending from the frame member 66 to resist the rotation of the tubular shaft 184 to rock the bushings 171, and to separate the form cylinders 25 and 26 from the blanket cylinders 23 and 24 respectively. The spring 187 also similarly acts to resist rotation of the tubular shaft in the opposite direction after it has been moved to trip the cylinders as described. The arm 183 has an extension 189 which is provided with a tool receiving socket 191 by which it, and through the hollow shaft 184, the arm 182 may be rotated to turn both bushings 171 simultaneously. A spring and ball locked pin 192 is provided in the extension 189 and arranged to be inserted in an opening 193 provided in an arm 194 to lock the arm 183 and the arm 194 together.

The arm 194 is rotatably mounted on the end of the hollow shaft 184 adjacent to the arm 183 and has an extension 195 to which links 196 are pivotally secured. The links 196 extend from the extension 195 to an arm 197 secured on the shaft 131 adjacent the frame member 67. Rocking movement of the common rock shaft 131 will, through the links 196 and arm 194 (when the pin 192 is in position to lock the arms 183 and 194 together), rock the hollow shaft 184 to cause the cylinder 25 to be separated from the cylinder 23. This rocking movement of the shaft 131 will also cause the cylinder 23 to be separated from the cylinder 24 by turning the bushings 166 through the arms 161, the links 162, and the rings 164 in a similar manner. When the pin 192 is withdrawn from the arm 194, only the form cylinder 25 will be moved to separate it from the blanket cylinder 23, when the arm 183 is turned by a tool inserted in the socket 191.

The handle 181 is used to adjust the impression pressure, or the degree of engagement of the form on the cylinder 25 with the blanket on the cylinder 23, and a scale 198 and a handle locking means 199, (shown in Figure 2), is provided to indicate such adjustment and to lock the handle 181 in its adjusted position. When the handle 181 is locked in position, the shaft 179 is held stationary and the arms 178 through the links 177 hold the lower ends of the links 175 to insure movement of the bushings 171 as above described by rocking movement of the hollow shaft 184.

The means whereby the form inking rollers 49 and 50 are tripped or separated from the form cylinders 25 and 26 respectively, includes sleeves 201 (see Figures 7 to 9), rotatably mounted upon the hubs 169 of the bearing supporting bushings 171, and which are connected by links 202, each secured at one of their ends to lugs 203 provided on the sleeves 201, and at their other ends to arms 204 and 205 (shown also in Figure 2), which are secured one at each end of the shaft 186 adjacent the frame members 66 and 67 respectively. A coiled spring 206 is provided and arranged to react between the arm 204 and the stationary stud 188 to resist rotation of the shaft 186 to rock the bushings 171. The arm 205 has an extension 207 (best shown in Figures 2 and 15), provided with a tool receiving socket 208 by which it, and through the shaft 186, the arm

204 may be rocked to simultaneously rock the sleeves 201. A spring and ball locked pin 209 is provided in the arm 194 and is arranged to be inserted in an opening 211 provided in the extension 207 to lock the arms 205 and 194 together whereby the sleeves 201 will be rocked whenever the shaft 131 is rocked.

The sleeves 201 are each provided with a cylindrical surface 212 (shown in Figures 7 to 9) eccentric to its axis and to the hub 169. A ring 213 is rotatably mounted upon each eccentric 212 and is retained against rotation by links 214 pivotally connected at one end to the adjacent frame member 66 and 67 respectively, and at their other ends to a lug 215 provided on the respective ring 213. The rings 213 are held against the side frames by screws 216, screw-threaded into the adjacent frame member 56 or 67, elongated openings 217 being provided in the rings 213 to permit their movement in the general direction of the arrow 160, when the sleeve 201 is turned.

Arms 218 and 219 (see Figures 8 and 9), are pivoted at their adjacent ends to the rings 213 (intermediate the ends of the form inking rollers 49 and 50) by pivot screws 220 and extend away from each other over and along the ring 213. The remote end 221 of each of the arms 218 and 219 has a pin 222 pivotally journaled therein into which an adjusting screw 223 is screw-threaded. The screws 223 are rotatably mounted in lugs 224 (see Figure 10), which are pivotally mounted in the ring 213. The screw heads 225 are under constant urge away from the lugs 224 by coiled springs 226 arranged to react between one side of the lugs 224 and the respective screw heads 225. A stop nut 227 screw-threaded on each of the screws 223 is pinned thereto and engages the other side of the lug 224. The springs 226 resiliently maintain the remote ends 221 of the arms 218 and 219 in their adjusted position.

The arms 219 and 218 are connected by links 228 to split ink roller sockets 229 and 231 respectively, and these sockets 229 and 231 are carried on arms 229a and 231a respectively, each of these arms being rotatably mounted upon the inner end of a supporting sleeve 230 disposed one at each end of the roller 48 and which also act to secure the roller bearing 99 in position. The links 228 are pivotally connected to the arms 218 and 219 intermediate their pivotal connection with the ring 213 and the pin 222. The arrangement is such that when the ring 213 is moved toward the rollers 49 and 50 by the rotation of the eccentric 212, the ink roller sockets 229 and 231 will be swung about the axis of the ink roller 48 and be separated from the form cylinder.

The rollers 49 and 50 are each journaled in sleeves 232 which are eccentric to the axis of the rollers 49 and 50 and have a central portion reduced in diameter so as to form what may be termed a dumb-bell shaped bearing. The sleeves 232 are clamped in the respective bracket 229 and 231 by a clamp screw 233 which acts on a swing cap 234 in the usual manner. A roller bearing 235 (see Figure 7), is disposed in each of the ends 236 and 237 of the sleeves 232. Rotation of the sleeves 232 will adjust the respective roller 49 or 50 in respect to the reciprocating roller 48 and the amount of this adjustment is indicated by comparison of a dial and pointer 240.

A vertically extending rod 238 (see Figures 1 and 2), is connected at its lower end to the extension 207 of the arm 205 (see also Figure 16), and at its upper end to one arm 239 of a bell crank 241 pivotally secured to the frame mem-

ber 67 by a screw 242. The other arm 243 of the bell crank 241 is connected by a horizontal rod 244 to the catch member 86. The rod 244 passes through a lug 245 provided on the catch member 86. Springs 246 and 247, one on each side of the lug 245, react between this lug and collars 248 and 249 respectively, which are secured to the rod 244. The catch member 86 is pivoted to the frame member 67 by a screw 251 and is adapted to be swung into the path of the lip 87 on the arm 85 of the lever 73 whenever the arm 205 is rocked to trip the ink form rollers 49 and 50 through the rods 238 and 244. It will be understood that the engagement of the lip 87 by the catch member 86 acts to prevent the ductor roller 42 from contacting with the fountain roller 41 when the form rollers are tripped "off" or disengaged from the form.

The mechanism employed to trip the printing cylinders and inking rollers, and the ductor roller operating mechanism of the upper portion of each of the printing units 21 are shown in Figure 2. Although not shown in the drawings, it will be understood that tripping mechanism similar to that shown in Figure 2, is employed for moving the form cylinders 26 away from their cooperating blanket cylinders 24, and for tripping the form rollers away from the form cylinders 26; also that additional mechanism similar to that depicted in Figure 2, is provided for operating the ductor rollers and other members that are duplicated in the lower portion of the printing units. The mechanism for tripping the cylinders and rollers in the lower portion of each unit is operated by a second arm 197 not shown, but also secured on the shaft 131, and connected to the tripping mechanism in substantially the same manner as that shown for the upper portion of the unit.

During the time that the press is being made ready for a run, and especially when several men are each working on different units of the press, it is desirable that mechanism be provided whereby the operator of any unit can so set the tripping mechanism that the unit will be tripped "on" impression and be locked there so the impression cannot be tripped "off" by an operator on any of the other units, and also, it is desirable that mechanism be provided whereby the operator can set the tripping mechanism of the unit on which he is working, to trip the impression "off" and it will be locked there and the unit will be held "off" impression until it is unlocked. Manually operated means is provided to separately lock each of the levers 134 (see Figures 2, 12 and 13) in a position to trip the cylinders and rollers of any unit 21 "on impression", and to lock them in such tripped position, and these means also provide for tripping "off impression," the cylinders and rollers of any unit 21 and locking them in such tripped position. These means include a spring pressed pin 252 (Figure 13) which is slidably mounted in the end of the arm 139 and secured in the handle 143. Two spaced apart holes 253 and 254 are provided in the frame member 66 and adapted to receive the pin 252 and lock the lever 134 in the above-mentioned positions respectively. In Figures 2, 12 and 13, the lever 134 is shown locked in the "impression on" position, with the pin 252 of the arm 139 extending into the hole 254. The pin 252 may be drawn into the arm 139 by pulling upon the handle 143 and then slightly rotating it to move the hole 255 provided therein, out of

alignment with a pin 256 secured in the arm 139 and protruding therefrom. This operation will hold the pin 252 in inoperative position and the lever 134 will be free and can be swung by the solenoid 158, through the rod 44. It will be understood that the lever 139 may be swung to bring the pin 252 into alignment with the hole 253 and by then turning the handle 143 to bring the hole 255 into alignment with the pin 256 that the pin 252 will then be projected into the hole 253 and lock the tripping mechanism in the "impression on" position. When a lever 139 is thus locked in either the "impression on" or "impression off" positions, if the solenoid 158 is energized, it will have no effect on it or on any lever 139 that is in a locked position, as the springs interposed between each lever and the rod, permit motion of one without moving the other.

Assuming that the printing machine is in operation and for some reason it is desired to trip or separate the movable blanket cylinder 23 from the other blanket cylinder 24, the form cylinders 25 and 26 from their cooperating blanket cylinders, and the inking rollers from their respective form cylinders on all of the units 21 simultaneously, an operator closes the switch 156 to energize the solenoid 158. Energization of the solenoid 158 will, through the bell crank 159, push the rod 144 to the left in Figure 1 to compress the springs 155, whereupon pressure will be exerted to turn the lever 134 from its normal neutral position to swing the reciprocating arm 118 of each unit 21 in the proper direction to cause the catch shoulder 124 to engage the pin 126 and rock the shaft 131 counter-clockwise in Figures 1 and 2. This rocking movement of the shaft 131 will simultaneously rock the eccentric bushings 166 to trip all of the blanket cylinders 23, and through the link 196 rock the arm 194. As the pins 192 and 209 are both inserted in their respective openings 193 and 211 in the arm extensions 195 and 207 respectively when the machine is in operation, rocking movement of the arm 194 will simultaneously rock the eccentric bushings 171 and the sleeves 201, tripping all of the form cylinders 25 and 26 to separate them from the respective blanket cylinders 23 and 24 and all of the ink form rollers to separate them from the form cylinders 25 and 26. At the same time that the above cylinders and roller tripping actuation takes place, the swinging movement of all of the ductor rollers 42 is stopped due to the engagement of the catch member 86 with the lip 87.

Should it be desired to trip only the blanket cylinder 23 of one of the units 21, the pins 192 and 209 are withdrawn and the shaft 131 may be rocked by a wrench applied to the wrench lug 129. By withdrawing only the pin 209 and leaving the pin 192 in locking position, the form cylinders 25 and 26 may be tripped simultaneously with the blanket cylinder 23 of the selected unit 21. Occasionally it is desirable to trip only the form cylinder 25 of a selected unit 21 and by withdrawing the pin 192, this may be accomplished by inserting a tool in the socket 191 and rocking the hollow shaft 184 thereby. Likewise, it may be desired to trip only the ink form rollers to separate them from the form cylinder 25, and this is accomplished by withdrawing the pin 209 and rocking the shaft 186 by a tool inserted in the socket 208.

From the foregoing, it will be understood that the printing impression may be manually tripped by moving the blanket cylinder 23 out of printing

relation with the blanket cylinder 24 if the pins 192 and 209 of both the upper and lower printing units are removed from their locking position and rotating the shaft 131 by means of a wrench applied on its squared end 129. Any of the form cylinders may be disengaged from its coating blanket cylinder by withdrawing the pin 192 from its locking position and turning the sleeve 184 by means of a bar inserted in the socket 191, and the form rollers in any printing unit may be separated from the form by withdrawing the pin 209 from its locked position and rotating the shaft 186 by a tool inserted in the socket 208.

In machines of this kind as heretofore constructed, the inking rollers have been carried on vertically movable plates or light frame members, by means of which they are lifted from the form, usually by cam mechanism, and when the rollers are lowered into engagement with the form they are held in contact with it by gravity, thus allowing the rollers a certain amount of freedom which permits them to bounce as they are engaged and disengaged from the plate or form as it passes under them. With the eccentrically controlled roller operating mechanism as herein disclosed, the rollers are positively held in both the non-engaging and in the engaging positions and a much smoother and positive action results.

Form inking rollers used in machines of this kind have heretofore been rotatably supported in 30 roller sockets secured to the frame members, and while screw adjusting means for positioning these sockets to give the desired contact pressure of the rollers were provided, adjusting one of these sockets, required first the loosening of one or more bolts which secured the socket to the frame, then adjusting one or more adjusting screws to regulate the pressure and finally tightening the bolts. It will be seen that with the arrangement herein disclosed, the adjustment of any form roller socket with relation to the form cylinder is effected by turning but one screw which is automatically locked in position.

In order to provide for variation in the diameter of the ductor roller, the mechanism for supporting and swinging the ductor rollers provides means for adjusting the axial distance of the ductor roller from the fountain roller by rotation of the eccentric bushings in which the bearings are carried. The pressure of the ductor roller against the ink roller toward which it is swung by the rotation of the cam 61 is separately adjusted by properly positioning the screw 78 in the slot 77. Those versed in the art will appreciate that this is a simpler form of adjustment than those heretofore known. Furthermore, with a variable stroke adjustment thus provided, the cam roller 82 is always in engagement with the cam 61 and the start and finish of each swinging movement is gradual and smooth, which contrasts with the abrupt starting and finishing swinging movement obtained by the ductor roller swinging mechanisms usually employed in which the cam roller leaves the cam while the ductor roller is in contact with one of the other of the rollers between which it swings.

Where reference is hereinafter made to "mechanism for applying liquid to a form," the term "liquid" is intended to include all kinds of ink that may be applied by the mechanism herein disclosed and also all of the moistening solutions used in lithography.

It will be understood that the invention may be embodied in other specific forms without departing from the spirit or essential attributes there-

of, and it is therefore desired that the present embodiments be considered in all respects as illustrative and not restrictive, and it will be further understood that each and every novel feature and combination present in or possessed by the mechanism, herein shown and disclosed, forms a part of the invention included in this application.

What I claim is:

- 10 1. In a printing machine, a mechanism for applying a liquid to a form on a form cylinder including a roller mounted for rotatable and axial movement between spaced apart machine frame members, means to rotate the roller, a gear casing having a worm rotated by the rotating roller and a worm gear driven by the worm disposed therein, a crank pin revolving with the worm gear, and a member connected to one of the frame members and to the gear casing and rocked by the crank pin to axially reciprocate the roller when the roller is rotated.
- 15 2. In a printing machine, a mechanism for applying a liquid to a form on a form cylinder including a roller mounted for rotatable and axial movement between spaced apart machine frame members, means to rotate the roller, a shaft end on the roller extending beyond one of the frame members, a casing carried by the shaft end, a revolving crank pin on a rotatable member journaled in the casing, means carried by the shaft end to rotate the rotatable member when the roller is rotated, means adjustable to vary the throw of the crank pin, a lever adapted to be rocked by the crank pin when it is revolved, and links connecting the lever to a frame member and to the casing, to axially reciprocate the roller when it is rotated.
- 20 3. In a printing machine, a mechanism for applying a liquid to a form on a form cylinder, including a roller mounted for rotatable and axial movement between spaced apart machine frame members, means to rotate the roller, a shaft end on the roller extending beyond one of the frame members, a casing carried by the shaft end, a worm on the shaft end in the casing, a worm gear in the casing to be driven by the worm, a crank pin driven by the worm gear, a lever pivoted on the crank pin, a link between one of the frame members and one end of the lever, and a link between the other end of the lever and the casing.
- 25 4. In a printing machine, a mechanism for applying a liquid to a form on a form cylinder, including a roller mounted for rotatable and axial movement between spaced apart machine frame members, means to rotate the roller, a worm rotated by the rotating roller, a worm gear driven by the worm, a crank pin extending through the worm gear eccentric to its axis, means to lock the pin to the worm gear, a portion of the crank pin extending beyond a side of the worm gear, the extending portion being eccentric to the axis of the pin, a lever pivotally mounted on the extending portion, a link connecting one end of the lever to one of the frame members, and means connecting the other end of the lever to the roller.
- 30 5. In a printing machine, an inking roller having a shaft rotatable therewith, and means for reciprocating the roller including a speed reducing gear supported in a housing and operable by rotation of the shaft, the shaft being rotatable with respect to the housing although axial motion of the shaft with respect to the housing is prevented, a crank connected to said speed

reducing gear and revolved thereby, a lever having an intermediate point connected to the crank and having one end connected to a fixed point on the machine and the opposite end connected to the housing, whereby rotating the shaft will revolve the crank and effect axial reciprocation of the roller.

6. In a printing machine, an inking roller having a shaft rotatable therewith, and means for reciprocating said roller including a speed reducing gear supported in a housing and operable by rotation of the shaft, the shaft being rotatable with respect to the housing although axial motion of the shaft with respect to the housing is prevented, a crank connected to said speed reducing gear and revolved thereby, means for adjusting the throw of the crank, a lever having an intermediate point connected to the crank and having one end connected to a fixed point on the machine and the opposite end connected to the housing, whereby rotating the shaft will revolve the crank and effect axial reciprocation of the roller.

7. In a printing machine, an inking roller having a shaft rotatable therewith, and means for reciprocating said roller including a speed reducing gear arranged within a housing supported by the shaft and secured thereto to reciprocate with the shaft, bearings between the shaft and the housing permitting rotation of the shaft with respect to the housing, a pair of crank pins connected to the speed reducing gear and revolved thereby, levers oscillated by the crank pins, and connections between the levers and fixed points on the machine; said fixed points being in a plane passing substantially through the axis of the shaft whereby when the shaft is rotated and the crank pins revolved, the roller will be reciprocated without imposing appreciable bending strain on the shaft.

8. In a printing machine, an inking roller having a shaft rotatable therewith, means for reciprocating the roller including a speed reducing gear supported in a housing and operable by rotation of the shaft, the shaft being rotatable with respect to the housing, although axial motion of the shaft with respect to the housing is prevented, an adjustable throw crank mechanism connected to the speed reducing gear having a crank revolved thereby, connections between the crank and a fixed point on the machine, whereby rotation of the roller effects a reciprocating action of the housing and the roller, said adjustable crank mechanism including a shaft eccentric to a rotating element of the reducing gear, the said shaft having an eccentrically positioned crank, means to rotate the shaft with respect to the rotating element to vary the throw of the crank, and means to secure the shaft to the rotating element.

9. In a printing machine, a roller mounted for rotatable and reciprocable axial movement between spaced apart stationary frame members, means to rotate the roller, a shaft end on the roller journaled in and extending beyond one of the frame members, a worm on the shaft end, a worm gear mounted to be driven by the worm, a shaft eccentrically mounted in the worm gear, a gudgeon on an end of the shaft in the worm gear and being eccentric thereto, a lever pivoted on the gudgeon, a connection between one end of the lever and one of the frame members, and a connection between the other end of the lever and the roller, whereby the roller will be reciprocated when the worm gear is rotated.

10. In a printing machine, a roller mounted for rotatable and reciprocable axial movement between spaced apart stationary frame members, means to rotate the roller, a shaft end on the roller journaled in and extending beyond one of the frame members, a worm on the shaft end, a worm gear mounted to be driven by the worm, a shaft eccentrically mounted in the worm gear, a gudgeon on an end of the shaft in the worm gear and being eccentric thereto, a lever pivoted on the gudgeon, a link connecting one end of the lever to one of the frame members, and means including a link connecting the other end of the lever to the roller whereby the roller will be reciprocated when the worm gear is rotated.

11. In a printing machine, a roller mounted for rotatable and reciprocable axial movement between spaced apart stationary frame members, means to rotate the roller, a shaft end on the roller journaled in and extending beyond one of the frame members, a worm on the shaft end, a worm gear mounted to be driven by the worm, a shaft eccentrically mounted in the worm gear, a gudgeon on an end of the shaft in the worm gear and being eccentric thereto, a lever pivoted on the gudgeon, a connection between one end of the lever and one of the frame members, and a connection between the other end of the lever and the roller, whereby the roller will be reciprocated when the worm gear is rotated, means to rotatably adjust the shaft in the worm gear in respect thereto, and means to lock the shaft to the worm gear in any of its adjusted positions.

12. In a roller reciprocating mechanism, means to mount a roller for axial movement, a roller shaft end, and a stationary frame member in which the roller shaft end is rotatably and axially slidable, a rotatable member carried by the shaft end, means to rotate the member, a shaft extending eccentrically through the rotatable member, a gudgeon on each end of the shaft and eccentric to its axis, means at one end of the shaft to rotate it in respect to the member, means within the member to lock the shaft thereto, means at the other end of the shaft to actuate said locking means, a lever pivoted on each gudgeon, a link connecting a first arm of each lever to the frame member, and means to connect a second arm of each lever to the roller.

13. In a printing machine, a frame, a cylinder running in contact with a roller and reciprocable with respect thereto to effect liquid distribution, an extended shaft for the cylinder, and a self-contained reciprocating mechanism including a worm driven by rotation of the shaft, a worm-wheel, crank and lever connections, and a link on each side of the shaft having pivotal connections to the frame, the last named connections being on opposite sides of the axis of the shaft, whereby the axial thrust imposed by the reciprocating mechanism is balanced, and bending pressure on the shaft is avoided.

14. In a printing machine, a frame, a cylinder running in contact with a roller and reciprocable with respect thereto to effect liquid distribution, an extended shaft for the cylinder, and a reciprocating mechanism including a worm secured to the shaft, a gear support rotatable with respect to the shaft and prevented from motion therewith, a worm-wheel rotatable in the gear support and engaging the worm, aligned gudgeons rotating with the worm-wheel, a lever for each gudgeon and oscillated thereby, and a member connecting each lever pivotally to the frame, the axes of the pivotal connecting points of the said

members being in alignment and on opposite sides of the axis of the shaft, whereby axial thrust imposed by the reciprocating mechanism is balanced, and bending pressure on the shaft is avoided.

15. In a printing machine having a frame, a roller rotatably supported by the frame in bearings permitting its reciprocation, a shaft on the roller having a first gear thereon, a gear support on the shaft and held against axial motion with respect thereto, a second gear rotatable with respect to the support and in mesh with the first gear, an eccentric driving connection on the second gear, and connections from the driving connection to the support and to the frame, the connections to the frame being on opposite sides of the shaft, whereby rotation of the roller creates a force acting to reciprocate the roller without tending to bend the shaft.

16. In a printing machine having a frame, a roller rotatably supported by the frame in bearings permitting its reciprocation, a shaft on the roller having a first gear thereon, a gear support on the shaft and held against axial motion with respect thereto, a second gear rotatable with respect to the support and in mesh with the first gear, a lever arranged for swinging movement with respect to the gear support and connected to the second gear to be swung when it is rotated, and connections from the lever to the gear support and from the lever to the frame, the connections to the frame being on opposite sides of the shaft, whereby rotation of the roller creates a force acting to reciprocate the roller without tending to bend the shaft.

WILLIAM F. HUCK.
